COLLAPSIBLE HOISTING FRAME

Henry A. Pasternack, Brooklyn, N. Y., assignor
to David Levow, New York, N. Y.

Application February 18, 1937, Serial No. 126,342

4 Claims. (Cl. 294—67)

This invention relates to improvements in hoisting frames, being particularly directed to a collapsible unit formed of internesting elements in association with a handle serving, upon assembly of the elements, to lock the same in rigid and firm operative position.

Broadly, it is an object of this invention to provide a hoisting frame incorporating a plurality of internesting elements capable of angular displacement with respect to one another to form a grill or cage, and adapted to be locked in assembled position by the medium for supporting the same.

Specifically, it is an object of this invention to provide a hoisting frame incorporating a plurality of support elements, each in the form of a continuous loop and capable of internesting to form a knock-down assembly in substantially a single plane, the respective elements being pivotally mounted with respect to one another, so that, upon angular displacement about a body or package, an enclosing cage therefor may be provided, the handle for the frame being so formed and actuated as to lock the respective elements to provide a rigid device as assembled.

These and other advantages, capabilities and features of the invention will appear from the subjoined detailed description of one specific embodiment thereof illustrated in the accompanying drawing, in which

Figure 1 is a perspective view showing my hoisting frame as assembled.

Figure 2 is a front elevation showing my hoisting frame as collapsed.

Figure 3 is a perspective view of the locking handle.

Figure 4 is an end elevation in section taken along lines 4—4 of Figure 2.

Referring to the reference characters in the drawing, my hoisting frame comprises a plurality of elements A and B, each provided in the form of a substantially rectangular continuous loop and having respectively faces 10 to 13 inclusive and 14 to 17 inclusive, the ends of the bars forming the elements being interlocked as at 18; the element A is smaller in length and height than element B, so that it may nest within element B, as shown in Figure 2, when the device is in knock-down condition.

The respective elements A and B are interconnected by pivot members respectively at their heads and bases 10—12 and 14—16, such pivots being formed, for the purpose of illustration, of rivets 19, applied as shown in sectional view of Figure 4.

A locking handle 20 for the device comprises, in this illustration, of a wire bent to form a triangle having legs 21 and 22 merging at apex 23, the portions of the wire 24 and 25 forming the base of the triangle, having their free ends 5 extending to form arms 26 and 27 disposed at right angle to the base and legs of the triangle, the extremities of the arms 26 and 27 having up-standing projections 28 and 29.

As shown in Figures 1 and 2, the handle 20 is assembled to encompass the respective heads and bases 10—14 and 12—16 across their width; the handle being disposed so as to have the triangular legs thereof 21 and 22 adjacent the apex 23 rest against the surface of the head of element 10 B when the device is in collapsed form, while the arms 26 and 27 of the base are suspended below the undersurface of the head of element A. When the device is assembled through the angular displacement of element A with respect to 15 element B about the upper and lower pivot members 19, the handle may be drawn upwardly in the direction of the arrow in Figure 1, so that legs 21 and 22 rest within the apices 30 and 31 20 formed by the diametrically opposite heads of 25 the elements, while the projections 28 and 29 rest within the apices 32 and 33 formed by the diametrically opposite heads, the legs and projections above referred to being alternately disposed with respect to one another; thus forming 30 30 a four-point locking medium to rigidly maintain the assembled frame and prevent the respective elements A and B thereof from being displaced.

In order to load the hoisting frame, the same is taken in the collapsed form (see Figure 2) and 35 material in the form of a package or in a tub 34 is disposed on base 12 of element A; the element B is then displaced about pivots 19 at the heads and bases of the respective elements so that, upon angular displacement, in this instance, 40 right angular displacement of the respective elements, a barred or griled cage for the package is provided; the handle 20 is then drawn upwardly (see Figure 1) by application of hook 35 acting on apex 23 thereof, so that the respective 45 legs 21 and 22 and projections 28 and 29 enter into the apices between the respective portions of the heads of the elements to lock the device.

To remove the package the hook 35 is withdrawn from the apex of the handle, permitting 50 the handle to drop by gravity, thus releasing the pressure of the legs 21 and 22 and projections 28 and 29 against the portions of the heads of the respective elements at their apex formations; whereupon element B may then be pivotally dis- 55

placed about element A to cause collapsing and internesting of such elements.

It is obvious that various changes and modifications may be made to the details of construction without departing from the general spirit 5 of the invention as set forth in the appended claims.

I claim:

1. In a hoisting frame, a plurality of support 10 members capable of nesting one within the other, means for mounting said members to permit angular displacement thereof to form an enclosing cage, and means adapted to be positioned at the respective apices defined by the support members 15 when disposed in angular relationship, for rigidly locking the supports and maintaining said enclosing cage formation.

2. In a hoisting frame, a plurality of support members capable of nesting one within the other, 20 means for mounting said members to permit angular displacement thereof to form an enclosing cage, and means adapted to be positioned at the respective apices defined by the support members 25 when disposed in angular relationship, for rigidly locking the supports and maintaining said enclosing cage formation, said last named means comprising a handle having formations at a plurality of points normally out of contact with the support members when the same are in nested 30 form and adapted, upon being vertically displaced

and maintained under tension, to rest in the aforesaid apices.

3. In a hoisting frame, a plurality of polygonal support members capable of nesting one within the other, means for pivotally mounting said 5 members to permit angular displacement one with respect to the other to form an enclosing grill or cage, and means adapted to be disposed at the apices defined by a plurality of adjacent faces of the respective support members when 10 disposed in angular relationship for rigidly maintaining said support in angular position.

4. In a hoisting frame, a plurality of polygonal support members capable of nesting one within the other, means for pivotally mounting said 15 members to permit angular displacement one with respect to the other to form an enclosing grill or cage, and means adapted to be disposed at the apices defined by a plurality of adjacent faces of the respective support members when 20 disposed in angular relationship for rigidly maintaining said supports in angular position, said last named means comprising a handle having formations at a plurality of points normally out of contact with the support members when the 25 same are in nested form and adapted, upon being vertically displaced and maintained under tension, to rest in the aforesaid apices.
